Primary Examiner — Charles D Hanson*(74) Attorney, Agent, or Firm* — Price Heneveld LLP(57) **CLAIM**

We claim the ornamental design for a border dressing, as shown and described.

DESCRIPTION

FIG. 1 is a front perspective view of a border dressing of the present disclosure;

FIG. 2 is a rear perspective view of the border dressing of FIG. 1;

FIG. 3 is a front elevational view of the border dressing of FIG. 1;

FIG. 4 is a rear elevational view of the border dressing of FIG. 1;

FIG. 5 is a first side elevational view of the border dressing of FIG. 1;

FIG. 6 is a second side elevational view of the border dressing of FIG. 1;

FIG. 7 is a top plan view of the border dressing of FIG. 1; and,

FIG. 8 is a bottom plan view of the border dressing of FIG. 1.
